KNOCKDOWN SHEET METAL CABINET

Harold Lew, Brooklyn, N. Y.

Application May 16, 1946, Serial No. 670,196

5 Claims. (Cl. 312—144)

1

This invention is an improvement in cabinets, particularly cabinets to be produced in knock-down form for convenience in shipping, and easily assembled for the use by the ultimate owner.

The object of the invention is to provide a cabinet preferably made of metal and comprising relatively few parts of simple design, and shaped at their engaging portions so as to be capable of easy connection when set up to give the cabinet its final form.

A further object of the invention is to provide a metal cabinet with shelves on the interior and with members for supporting the shelves adapted to be engaged by parts of the body of the cabinet at the sides and back, so that they can be secured without extra small fastening devices such as bolts, screws, and nuts; said members having grooves so that the shelves can be quickly mounted and held in their proper places.

The nature and advantages of the invention are clearly set forth in the ensuing detailed description, taken with the accompanying drawings; but the structure disclosed is offered by way of explanation only and I do not wish to be necessarily limited to the exact details of the cabinet which the drawings present.

On the drawings:

Figure 1 is a front view of the parts of a metal cabinet according to my invention, disconnected from one another but in readiness to be joined together;

Figure 2 is a vertical section of the assembled cabinet taken on a plane passing through the cabinet from front to back;

Figure 3 is a perspective view of one of the sides of the cabinet;

Figure 4 is a similar view of the back thereof;

Figures 5 and 6 are perspective views of the shelf supporting members to be disposed at the sides and back respectively within the cabinet;

Figure 7 is a perspective view of the top of the cabinet;

Figure 8 is a perspective view of the bottom or base of the cabinet;

Figure 9 is a perspective view of the lower part of the cabinet showing how the sides and back stand on the bottom;

Figure 10 is a perspective view showing the cabinet complete with all the parts, including the doors, in position;

Figure 11 is a plan view in part of the back, sides and door, the top being removed; and

Figure 12 shows a detail.

The numeral 1 indicates a member to form the back of the cabinet, 2 the top thereof, and 3 the

2

bottom. The top and bottom are attached to the upper and lower edges of the back 1 by means of hinges 4, these hinges being of the well-known two-leaf type connected by a pin so that when the leaves of the respective hinges are moved together with the bores or bearings for the pin in alignment, the two leaves of the hinge can be united by merely slipping the pin into place. The sides 5 are attached at their rear edges to the back 1 by similar hinges 6; the sides having flanges along the upper edges with openings that register with openings in the top 2, so that the top and the sides can be secured to one another with bolts and nuts, the holes in the top 2 for this purpose being indicated at 7 and the holes in the upper parts of the sides being indicated at 8. The cabinet also includes doors 9 in front secured to the forward edges of the sides by the same kind of hinges 10.

The back 1 has a horizontal flange 11 along its upper edge and the vertical lateral edges of the back are shaped so as to make vertical channels 12; these being formed by bending said edges over and inward as required. The outer edges of these two channels may be doubled over or beaded to reinforce same. These channels are open at their lower ends to permit the back to receive and hold a shelf supporting member or plate 13 which, as indicated in Figure 6, is shaped to provide horizontal transverse channels 14 that may be square in cross-section. The back 1 and the plate 13 can be assembled by slipping the member 13 into the channels 12 at the lower ends and the channels 12 will overlap this member 13 along its vertical edges and hold it when the back 1 stands upright. The top edge 16 of the member 13 will coincide with the outer edge of the flange 11 and along the lower edge 15 of this member or plate 13 is a shoulder 15 so that the plate will fit the rear side of the bottom or base 3.

As indicated in Figure 2, the edges of the top 2 are down-turned and in-turned to provide inside channels 17 extending all around the lower face of the top. The bottom 3 has a shoulder 18 on its upper face extending all around it, and rests upon the down-turned edges 19. Within the compass of the shoulder 18 the bottom is higher, and the back 1, the sides 5, and the shelf supporting member 13, as well as similar members 23 at the sides 5, stand upon this shoulder when the parts are all united.

Each of the sides 5 has an over-turned horizontal flange 20 along its upper edge, and its vertical rear edges 23 are doubled over for re-

inforcing effect. The front vertical edges of the sides are shaped to provide channels 22 like the channels 12; and associated with each side will be a shelf supporting member shown in perspective in Figure 5 at 23 with similar transverse horizontal channels 14 which match and register with the channels of the member 13. The members 23 have shoulders 24 at the top and may be so shaped along the lower edges 25 that they rest on lower flanges 20 of the sides 5 but leave the holes therein uncovered.

The parts of the cabinet are attached to one another by laying the back in a convenient position and inserting the members 13 into the channels 12 at the lower ends thereof. The members 23 are then inserted into the channels 22 at the front of the sides 5 by movement edgewise into these channels, and between the upper and lower flanges 20. The top 2 and bottom 3 are then secured to the back 1 by the hinges 4. Parts of these hinges 4 are affixed to the top 2 within the channel 17 along the rear; and the complementary parts are attached to the member 13, the flange 11, or both, on the upper edge of the back; the bottom 3 is connected by hinges 4, parts of which are made fast to the upper face thereof at shoulder 18 in the rear, and the complementary parts to the correct points on the member 13. The respective parts are connected by inserting the pins as above stated. The top 2 and bottom 3, as indicated in broken lines on Figure 2, can then be folded against the inner face of the back 1. This much can be done at the factory, so that the back, top and bottom may be handled and shipped as a unit.

To finish the cabinet, the back 1 is held upright, and the bottom 3 and top 2 are swung to horizontal positions. One side 5 is now stood on the bottom 3, and its upper flange 20 supports the top 2 along one side of the latter. The rear edge 21 of the side 5 now makes contact with the adjacent vertical edge of the back, and the leaves of hinges 6 are pinned together. Now the sides 5 and back 1 rest upon the bottom 3 by standing on the horizontal shoulder 18; and the bottom shoulder 15 of the plate 13 engages the bottom 3 along its rear. See Figure 2. Bolts or pins are next inserted into the holes 7 and 9 from the inside of the channel 17, and the side also is secured by pins or bolts passed through the holes 8 thereof in the holes 7 of the bottom. Along the sides and back of the cabinet the grooves 14 are continuous except at the inner corners at the junction of the sides and back, where the ends of the grooves 14 in the plates 13 are covered by the side channels 12. The shelves shown at 26 however, can be notched at the rear corners 30 to clear these channels and make a snug fit with the inside of the cabinet along the sides and rear; being of course unsupported in front.

After the one side 5 is thus set up and fastened, the shelves 26 are put in; and then the other side is mounted on the bottom and fastened to the bottom, top and back in the same way; the other plate 23 receiving the adjacent ends of the shelves 26. The horizontal surface of the shoulder 18 is no wider than the widths of the channels 12 and 22, so that the outer faces of the sides 5 and back 1 and the vertical faces of the bottom 3 are flush with one another.

The doors 9 are joined to the front edges of the sides by pinning together the parts of the hinges 10. These doors also are made of metal with their edges 27 overturned and then in-turned

and cut away at the corners 28 so as to present abutting beveled ends 29 which can be welded together. Thus on the inner faces of the doors along the edges are channels which pass all the way around the doors; and these doors are further strengthened by vertical longitudinal ribs 29, with ends under the overturned upper and lower edges. The doors fill the open front of the cabinet snugly, the overturned upper edges passing easily under the top and the overturned lower edges registering with the shoulder 20 in the front when the doors are closed.

From this description it will be seen that the objects of the invention are all nicely gained by the construction thus explained. The parts are easy to manufacture and can be assembled in a very short time with but little effort. They make a compact and strong cabinet which also has a neat, finished appearance.

In practice, the shoulders 24 at the top of the members 22 and the inside of the channels 17 of the top give ample space for the handling of the bolts and nuts that hold the sides and top together. To secure the lower flanges 20 of the sides to the bottom 3, bolts are passed through the holes 8 and into the holes 7, and then the bottom can be tilted a little to put the nuts on the lower ends of the bolts under the bottom.

The top also carries a pair of links or the like 31 hinged to the inner face and capable of being folded against said face. These links support a detachably engaged bar 32, upon which articles of various kinds may be suspended directly or by suitable hooks, as will be understood.

These links are especially useful if the cabinet is to be used as a clothes cabinet. As many links and bars 32 may be mounted within the cabinet as desired. Then it is only necessary to remove the shelves so that all the space in the cabinet is available for articles suspended from the horizontal bars 32.

Having described my invention, what I claim as new is:

1. A cabinet having a top, bottom, sides and back, the latter having its vertical lateral edges turned over and inward to form channels, and its top edge bent over to form a horizontal flange, the top having its edges turned downward and inward, one of said inturned edges resting on said flange, hinges connecting the said top to said flange, a shelf-supporting member having its lateral edges received in said channels, said member having a shoulder at its lower end engaging the bottom, and hinges connecting the member to the bottom, so that the top and bottom can be folded against said member before assembly of the cabinet.

2. A cabinet having a top, bottom, sides and back, the bottom having a horizontal shoulder round its edges on its upper face, the sides and back resting on the shoulder, the back having its vertical lateral edges turned over and inward to form channels, the sides having their rear edges turned over and abutting the turned-over edges of the back, and having their front edges turned over and inward to form similar channels, shelf-engaging members against the inner faces of the sides and having their front edges received by the channels thereof, and the member against the back having its side edges received in the channels of the back, the lower part of the members having horizontal shoulders abutting the shoulder on the bottom.

3. A cabinet according to claim 2, wherein the top has downturned and inturned edges and said

sides and back have overturned upper edges to form horizontal flanges and means for securing the top to said flanges.

4. A cabinet according to claim 3 wherein said sides also have inward extending flanges at their lower edges to rest on and be secured to the bottom.

5. A cabinet having a top, a bottom, sides and back, the top having its edges turned down and inward to form channels, the sides and back having overturned upper edges to form flanges, the top being pinned to said flanges of the sides, and hinged to said flange of the back, the bottom having on its upper face a shoulder round its edges, the sides having horizontal flanges at the lower edges pinned to the bottom on said shoulder, the back having channels along its vertical edges, shelf-engaging members against the inner face of the back with their side edges received within said channels, the member against the back having a shoulder along its lower edge hinged to the bottom adjacent the shoulder, the sides having ver-

tical channels along their front edges, and overturned rear edges engaging the channels on the back and shelf engaging members against the inner faces of the sides with their front edges in the channels thereof, said last-named members having flanges at the bottom engaging the shoulder thereon.
